UNITED STATES PATENT OFFICE.

JOHN FITZ GIBBON, OF BRONXVILLE, NEW YORK, ASSIGNOR TO THE FITZ GIBBON CO., INC., OF NEW YORK, N. Y., A CORPORATION OF NEW YORK.

DESIGN FOR A GLOVE.

Application filed March 19, 1927. Serial No. 21,213. Term of patent 3½ years.

To all whom it may concern:

Be it known that I, JOHN FITZ GIBBON, residing at Cedar Knolls, Bronxville, county of Westchester, and State of New York, have invented a new, original, and ornamental Design for a Glove, of which the following is a specification, reference being had to the accompanying drawing, forming part thereof.

I claim:

The ornamental design for a glove as shown.

JOHN FITZ GIBBON.
